UNITED STATES PATENT OFFICE.

ANDRÉ VARAUD, OF GENEVA, SWITZERLAND, ASSIGNOR TO TAVANNES WATCH CO. S. A., OF TAVANNES, BERN, SWITZERLAND, A CORPORATION OF SWITZERLAND.

MECHANICAL FUSE FOR ARTILLERY PROJECTILES.

Original application filed May 13, 1924, Serial No. 712,960, and in Switzerland August 2, 1923. Divided and this application filed June 24, 1925. Serial No. 39,237.

The invention refers to mechanical fuses of the type in which the release of the striker device is controlled by a rotary member, the angular position of which can be regulated prior to firing and which during the flight of the projectile is driven by a clockwork movement in a direction opposite to that in which it is turned while being set.

It relates more particularly to the body of such a fuse, the frame of the clockwork movement and the manner in which this frame is fixed in the hollow body of the fuse.

As is customary in the fuses of this type the regulating of the time of ignition is determined by the angular displacement of the rotary timing member with regard to the body of the fuse and it is indispensable for obtaining a precision of the firing that any relative movement between this rotary member and the body of the fuse is excluded once the timing of the fuse has taken place.

For obtaining this result in most of the fuses of this known type means are provided which are operated like a wedge at the moment of the departure of the projectile by the effects of inertia, in such a manner that the rotary member is wedged in the body of the fuse and thereby becomes rigidly fixed to the latter.

In practice these means do however not produce the result aimed at and often a disturbance takes place either during the loading of the projectile, since during the timing of the fuse and the moment of firing these wedging means are inoperative, or at the moment of firing because these wedging means do not then render the timing element integral with the body of the fuse with the requisite instantaneousness for preventing all disrupting actions at the moment of the angular inertia of the said timing element.

In other fuses of this known type, it has been proposed to house the frame of the clockwork in a cylindrical cavity provided in the body of the fuse, and to provide the rotatable timing member with a supporting surface and a tightening ring bearing thereon which is screwed into the entry of this cavity so as to immobilize the frame of the

clockwork and this timing member in the axial direction.

This manner of mounting the clockwork in the body of the fuse is defective in that the necessity for allowing the timing member the latitude of turning about itself may prevent the tightening ring employed for pressing the frame of the clockwork to the bottom of its cavity from being applied with sufficient pressure to prevent any untimely unscrewing of the ring during the timing and any disrupting action at the moment of the departure of the projectile.

Finally it has been proposed to house the frame of the clockwork in a cylindrical casing and to enclose this casing in the interior of a hollow fuse composed of two parts. This manner of mounting results, it is true, in obtaining a rigidity of the whole thus formed by the body of the fuse and the frame of the clockwork sufficient to prevent any action on the departure of the projectile tending to disturb the regulation of the fuse but in practice it is very difficult to accomplish this due to the fact that the casing above mentioned is in one piece and due to the absence of means for determining precisely and very quickly the relative angular position respectively of the frame in regard to the casing and of the latter in regard to the body of the fuse.

Now according to this invention a body of the fuse is provided, a frame of the clockwork of such a fuse and a method of mounting this frame in the interior of this fuse body which is made of two parts screwed one upon the other, enabling all the above disadvantages to be overcome by the employment of a cylindrical casing made in two semi-cylindrical parts presenting at its periphery longitudinal projections on diametrically opposite sides which cooperate with grooves correspondingly provided in the body of the fuse, thereby preventing any angular displacement of the casing in regard to the said body.

The drawing illustrates by way of example a constructional form of this invention applied to a mechanical fuse of the type described in my co-pending application Serial No. 712,960 filed May 13, 1924, also

in application, Serial No. 37,608, filed June 17, 1925, and Serial No. 38,498 filed June 20, 1925.

Fig. 1 is an axial section of a fuse embodying my present invention.

Fig. 2 is a transverse section taken on the line A—A of Fig. 1, and

Figs. 3 and 4 are respectively detail views illustrating elevations of the exterior and interior of one half of the casing.

In the drawing the movable parts of the fuse are not shown because they do not form part of the actual invention and their illustration seems unnecessary for the understanding of the object of the latter.

In the drawing 1 and 2 indicate the two parts of the hollow body of the fuse which are screwed one to the other so as to house between them the cylindrical casing 28. This latter is formed in two semi-cylindrical parts presenting each one an outer longitudinal projection or rib 33. When the two halves of the casing are united, these two projections assume diametrically opposite positions and engage at the moment of the mounting of the frame of the clockwork into the body of the fuse, with two corresponding longitudinal grooves provided in the interior of said fuse body.

These grooves and these corresponding projections 33 constitute a kind of dove-tail arrangement between the casing and the body of the fuse which on the one hand prevents any angular relative displacement between these two members, and on the other hand, does away with any uncertainty in the mounting for determining the angular relative position of the two members.

Arranged in the two longitudinal sections of the casing 28 re-inforced by the projections 33 are notches adapted to be engaged by corresponding tenons formed on the periphery of three transverse plates 29 upon and between which the movable parts of the clockwork are spaced and secured.

These plates 29 are housed in circular grooves provided in the interior wall of the casing 28 so as to form an absolutely rigid unit with the casing and with three discs 30, 32 and 31 superposed one to the other and which constitute the compact bottom of the clockwork frame. The outer discs 30 and

31 are fitted to the casing with the aid of diametrically opposed screws, whilst the intermediary disc like the plates above referred to, is provided with two diametrically opposed projections engaging with two corresponding notches in the casing.

This disc 32 is a steel washer serving to reinforce the bottom of the frame of the clockwork while the disc 30 is hollow in order to serve as a barrel for receiving the power spring of the clockwork.

The advantages of the fuse body as shown in the two last constructional forms are the following ones:

First of all it is possible to make only the shoulder from a sufficiently hard metal (steel or brass) for resisting the shocks due to inertia, it being possible to make the cap of the fuse of aluminum in order to reduce the total weight of the fuse, which constitutes an advantage which is highly valued in the exterior ballistics.

On the other hand these constructional forms make it possible to simplify the finishing of the hollow body of the fuse in which it is not necessary to have as precise dimensions as in the case of the first form in which it is the fuse itself and not only a shoulder which is directly assembled with the clockwork.

I claim as my invention:

1. In a clockwork operated mechanical fuse for artillery projectiles, a frame for the clockwork made of parts, and a casing made of two semi-cylindrical parts by which the parts of the frame are assembled one with the other.

2. A fuse as per claim 1 in which the front part of the frame comprises spaced transverse plates set into circular grooves of the casing so as to be supported on their whole periphery by the casing, said plates being rigidly connected with the casing in a revolute direction by means of tenons and notches.

3. A fuse as per claim 1, in which the rear part of the frame is constituted by three superposed disks rigidly connected with the casing by means of a unison effected by tenons and notches and by means of screws.

In testimony whereof I affix my signature.

ANDRÉ VARAUD.
